US00D508682S

(12) **United States Design Patent** (10) Patent No.: **US D508,682 S**
Yamada et al. (45) Date of Patent: **** Aug. 23, 2005**

(54) **SEMICONDUCTOR DEVICE**

(75) Inventors: **Tatsuya Yamada**, Yokohama (JP); **Kazuhiko Kurahashi**, Kawasaki (JP); **Toshihisa Inoue**, Yokohama (JP); **Taizo Tomioka**, Yokohama (JP); **Kazuo Shimokawa**, Yokohama (JP); **Yoshiki Endo**, Hyogo-ken (JP); **Masahiro Urase**, Himeji (JP); **Osamu Usuda**, Tatsuno (JP)

(73) Assignee: **Kabushiki Kaisha Toshiba** (JP)

(**) Term: **14 Years**

(21) Appl. No.: **29/206,162**

(22) Filed: **May 27, 2004**

(30) **Foreign Application Priority Data**

Feb. 23, 2004 (JP) 2004-005063

(51) LOC (8) Cl. **13-03**

(52) U.S. Cl. **D13/182**

(57) **CLAIM**

The ornamental design for a semiconductor device, as shown and described.

DESCRIPTION

FIG. 1 is a front, top and right side perspective view of a semiconductor device, showing our new design;

FIG. 2 is a top plan view thereof; the opposite side being a mirror image thereof;

FIG. 3 is a front elevational view thereof;

FIG. 4 is a right side elevational view thereof; the opposite side being a mirror image thereof; and,

FIG. 5 is a rear elevational view thereof.
